UNITED STATES PATENT OFFICE.

CHARLES WM. HAMPTON, OF SHEFFIELD, ENGLAND, ASSIGNOR OF ONE-HALF TO
C. & J. HAMPTON LIMITED, OF SHEFFIELD, ENGLAND.

VISE.

Application filed June 11, 1923, Serial No. 644,741, and in Great Britain September 1, 1922.

This invention relates to vises of the type in which the operating screw engages a detachable nut carried on a slide mounted in guides in the fixed jaw, its object being to 5 provide improvements in the construction, particularly in the form of the nut and in the means for supporting and detachably fitting it.

In vises of this type an abutment has been 10 provided on the fixed jaw to engage the slide portion of the nut, but according to the present invention the parts are shaped and arranged so that the abutment engages the nut adjacent to its tapped portion and between 15 that portion and its slide. By thus removing the abutment from proximity to the guides the stress on the latter when the vise is tightened is considerably reduced. The abutment may be, and preferably is, still 20 further removed from the guides by being spaced apart therefrom between them and the screw connection with the movable jaw, the nut being extended forward of its slide to engage the abutment. The nut prefer- 25 ably comprises a slide with bevelled edges and a central web carrying the tapped portion, this being a known form; but the central web extends forward of the slide, which engages undercut guides in the fixed jaw, 30 and the abutment engages the extended part of the web. Suitable means such as a pin passing through the base plate of the vise, are provided for retaining the nut in engagement with the guides and abutment.

35 In the accompanying drawings:—

Figure 1 is a sectional elevation of a vise according to the present invention.

Figure 2 is a sectional end view of Figure 1.

40 Figure 3 is an elevation of the detachable nut on a larger scale and Figure 4 is an end view of Figure 3.

Figure 5 is a central longitudinal section of Figure 1; and

45 Figure 6 is a transverse section taken on the line 6—6 of Figure 5.

Like reference numerals indicate line parts throughout the drawings.

50 The fixed jaw 1 of the vise is adapted to be secured to the bench by any suitable means and is provided with the usual aperture for the reception of the movable jaw 2 which is caused to slide therein on suitable

bearing surfaces or main guides 2^a by means of the operating screw 3 rotatably fitted to 55 the movable jaw 2 and engaging the tapped portion 4 of a detachable nut fitted to the fixed jaw 1. As shown in Figures 3 and 4 the detachable nut comprises a slide 5 having bevelled edges and a central web 6 carries the tapped portion 4. The fixed jaw 1 is provided with undercut guides 7, herein- 60 after termed secondary undercut guides, the slide 5 being formed to fit these guides. An abutment 8 is also formed inside the fixed 65 jaw 1 adapted to engage the detachable nut between its slide 5 and its tapped portion 4. Preferably, as shown in the drawings, the abutment 8 is spaced apart from the guides 7 and is situated between the sec- 70 ondary guides and the point at which the screw 3 is rotatably connected to the movable jaw 2, the web 6 of the detachable nut being extended forward of its slide 5 as shown at 9 and being formed with a bearing 75 surface 10 to fit against the abutment 8.

The rear end of the movable jaw 2 may be closed as shown at 11 (Figure 1) a suffi- 80 cient opening being left to clear the abut- 85 ment 8, and thus the screw 3 and nut may be protected from filings and the like. To assemble the vise the movable jaw 2 is first inserted into the aperture of the fixed jaw, the detachable nut is then caused to slide along the secondary guides 7 to engage the abutment 8 and is retained in this position by any suitable means such as a pin 12 pass- 90 ing through the base plate of the fixed jaw. Finally the operating screw 3 may be passed through the front of the movable jaw 2, 95 caused to enter the tapped portion 4 of the detachable nut and be engaged with the movable jaw 2 by the insertion of a pin 13 or the fixing of a collar placed thereon before engagement with the nut.

As the vise is tightened the abutment 8 will take the pressure, and its situation, removed from proximity to the secondary guides 7 and as near to the screw as practi- 100 cal will relieve these guides from the stress which would otherwise be placed on them due to the tendency of the rear part of the slide 5 to be lifted if, for example, the abut- 105 ment 8 engaged the forward end of the slide.

What I claim is:—

In a vise comprising a fixed jaw and a

jaw movable in guides thereon the combination of a screw rotatably connected to the movable jaw, secondary undercut guides on the fixed jaw, a slide detachably fitted in the secondary guides, a nut carried on the slide co-operating with the screw and extended forward of the slide towards the movable jaw and an abutment on the fixed

jaw spaced apart from the secondary guides between them and the screw connection with the movable jaw and engaging and supporting the front end of the extended portion of the nut. ¹⁹

In testimony whereof I hereunto affix my signature.

CHARLES WM. HAMPTON.
